UNITED STATES PATENT OFFICE.

ELWOOD C. BUNTING, OF PHILADELPHIA, PENNSYLVANIA, ASSIGNOR TO ROBERTS & MANDER STOVE COMPANY, OF PHILADELPHIA, PENNSYLVANIA, A CORPORATION OF PENNSYLVANIA.

LOCKING DEVICE FOR VALVES FOR GAS BURNERS.

Application filed November 23, 1924. Serial No. 752,775.

This invention relates particularly to gas ranges, in which there are two burners in the oven. One burner is in the upper portion of the oven for broiling and the other 5 burner is in the lower portion of the oven for baking.

The object of the invention is to provide means for locking one burner in the closed position when the other burner is open. 10 The locking mechanism is so designed that when both burners are closed, either burner can be opened.

In the accompanying drawings:

Fig. 1 is a side view showing two burners 15 of a gas range and the casing of an oven in section, and illustrating my improved locking mechanism;

Fig. 2 is an end view;

Fig. 3 is a view of one end of the locking 20 device;

Fig. 4 is a perspective view of one of the heads of the locking device; and

Fig. 5 is a view of the handle of one of the gas cocks.

25 The casing 1 of an oven of a gas range can be of any form desired. Located in the oven are two burners. One burner 2 is located in the upper portion of the oven and is used for broiling. The other burner 3 is in the lower portion of the oven and is used for baking. The burner 2 has a mixing chamber 4, which is provided with an air intake regulator of the ordinary type. Extending into the mixing chamber is a gas 35 nozzle 5, projecting from a gas cock 6 that is attached to the gas supply pipe 7. In the gas cock 6 is a valve 8 that has a handle 9. On this handle is a lug 10 that actuates the locking device 11.

40 The burner 3 has a mixing chamber 12. An air intake regulator of the ordinary type is provided for this burner. Extending into the mixing chamber is a nozzle 13 of a gas cock 14, which is connected to the 45 gas supply pipe 7. This cock has a valve 15, provided with a handle 16 having a lug 17. The two valve structures are similar in design.

The locking device 11 consists of a rod 18 50 that has a head 19 at each end. Each head has a bearing face 19^a with which the lug on the handle of the valve engages to move the locking device longitudinally to lock a valve. The movement of the lug is stopped

by a projection 24^a that forms a continuation of a stop 24 for locking the handle of a valve in the closed position. Each head has two fingers 20 and 21, which are spaced apart to form a form that spans the reduced shank 22 of the valve. On the finger 20 is 55 a projection 23, against which the lug on the valve strikes to move the locking device to neutral position with the valves closed. The rod can be of any length desired, depending upon the distance apart of the burners. 60

The device can be attached to any burner, as it engages only the shanks of the valves and is not attached to the main structure of the range.

70 The operation is as follows:—

As shown in Figs. 1 and 3, the gas valve, as it is turned on, raises the locking device as the lug 17 on the gas valve sweeps against the surface 19^a of the lower head 19, moving the locking device to the position shown 75 in Fig. 1, with the valve "on". This movement of the locking device brings the stop 24 of the upper head 19 into the path of the handle 9, which is in the "off" position, locking the handle from moving in the direction of its arrow, Fig. 1, to the "on" position. On closing the lower valve, the lug 17 strikes the projection 23 on one of the fingers of the head, retracting the locking device to the neutral position to allow either 85 valve to be moved to the "on" position.

When the upper valve is moved, it actuates the locking device, which engages the lower valve and holds it locked while the upper valve is open.

90 This device is simple and can be readily attached to burners in position, preventing the opening of one valve when the other valve is open.

I claim:

95 1. The combination in a locking device for the valves of gas burners, of two burners having gas-cocks with valves provided with handles, each of said handles having a laterally extending lug; and a locking device 100 having a forked head at each end to span the valve-stems, each head being shaped to be actuated by the lug on the handle of a valve to move the locking device to lock the valve at the opposite end of said device, 105 each head having a stop which is engaged by the handle to lock the valve in the closed position.

2. The combination in a gas range, of two gas-cocks spaced apart for controlling the gas admitted to the oven of the range, each cock having a handled valve, each handle having a lug; a longitudinally movable locking device for the valves, said locking device consisting of two heads and a rod, said heads

being detachably secured to the rod, each head being forked; a stop on one fork arranged to be engaged by the lug on the handle; and means on each head for locking its handle in the closed position. ¹⁰
